WHEEL MACHINE

Daniel W. Voorhees, Jr., Peru, Ill.

Application March 2, 1932, Serial No. 596,393

4 Claims. (Cl. 78—16)

My invention relates more particularly to machines for fastening the spokes into the hubs of metallic wheels.

One object of my invention is to combine in a wheel machine pneumatically operated portions for gripping and releasing the spoke and for holding the hub in proper position with mechanical means for performing upsetting operations upon the spoke to secure it into the hub.

Another object of my invention is the provision of means whereby the operation of the pneumatically operated portions of the machine may bear proper timed relation to the operation of the balance of the machine.

Another object of my invention is the provision of adjustments for the spoke heading devices whereby the beginning of the heading stroke of these devices is adjustable while the termination of the stroke remains constant.

Another object of my invention is the provision of spoke heading devices for forming a head upon the spoke both on the inside and on the outside of the hub and to impart to these devices different movements while operating them from a single driving connection.

Other objects of my invention will appear and be described in the specification.

The novelty of my invention will be hereinafter more fully set forth and specifically pointed out in the claims.

In the accompanying drawings:

Fig. 1 is a side elevation of a machine embodying my invention, the view being taken from the operating side of the machine.

Fig. 2 is a side elevation of the machine, the view being taken from the side opposite to that shown in Fig. 1.

Fig. 3 is a plan view of Fig. 1, the upper part of the machine being broken away, the section being taken about on the dotted line 3—3 of Fig. 1.

Fig. 4 is an end view of the machine viewed from end opposite to that at which the operator is placed.

Fig. 5 is a diagrammatic view illustrating the movement of the linkage of part of the upper portion of the machine.

Fig. 6 is an enlarged detail of some of the clutch and pneumatic control devices.

Fig. 7 is an enlarged detail showing a portion of a hub, a portion of a spoke, and several portions of the machine in proper relative positions before the commencement of a heading stroke.

Fig. 8 is a view corresponding to Fig. 7 showing the parts in proper relation at the completion of a heading stroke.

Fig. 9 is a sectional detail taken on the dotted line 9—9 of Fig. 1 looking to the left.

Fig. 10 is a detail of a portion of the heading mechanism the view being partly in section and some of the associated parts being removed.

Fig. 11 is a view of a portion of the hub advancing mechanism, partly in section and removed from its association with other portions of the machine.

Fig. 12 is an end view of the right-hand portion of Fig. 11.

The same numerals of reference are used to indicate identical parts in all the figures.

Broadly stated, my machine contemplates a complete operation comprising several steps which must be performed in their proper sequence to accomplish the desired result.

First:—There must be quickly operable and angularly adjustable means for properly holding the hub.

Second:—There must be gripping dies for holding the spoke during the heading operation.

Third:—There must be a heading tool to engage and head the spoke inside the hub.

Fourth:—There must be means for moving both the hub and the inside heading tool toward the spoke holding dies to form a collar on the spoke against the outside of the hub.

Fifth:—There must be means whereby to disengage the spoke from the gripping dies and permit a partial rotation of the hub to position it for the next succeeding spoke.

As illustrating one form of machine embodying my invention though without limiting myself to the precise details of construction and arrangement of parts shown in the drawings and to be herein described, but availing myself of all changes and modifications which may be made within the scope of the appended claims, I have shown a machine which I will describe by dividing it into a number of groups of elements.

Frame work

The frame work of the machine comprises an elongated bed 13 which, near its left end as shown in Fig. 1, carries a pair of upwardly projecting housings 14, and near the center of its length the bed 13 carries a pedestal 15. A knee 16 is adjustably mounted on the end of the bed 13 opposite to that which carries the housings 14. An auxiliary frame 17 projects laterally from the bed 13, as shown more clearly in Fig. 3.

Adjacent one of the housings 14, the bed 13 carries a bearing 18 (best shown in Figs. 3 and 4) and the auxiliary frame 17 carries a pedestal 19.

which is provided, among other things, with bearings 20 and 21, a bearing 22 being carried by one of the housings 14 and in line with the bearing 21, the bearings 18 and 20 being also in alinement.

5 *Main driving connections*

A driving shaft 23 is mounted in the bearings 21 and 22 and carries a pinion 24 which meshes with and drives a gear 25 loosely mounted on a 10 shaft 26 which is mounted in the bearings 18 and 20, the gear 25 carrying one member 27 of a dental clutch, the other member 28 of the dental clutch being splined upon the shaft 26, the latter carrying a crank disc 29 on the crank pin of which a 15 connecting rod 30 is mounted.

The shaft 26 has a disc 31 fast upon it, the latter carrying a pin 32.

20 *Auxiliary driving connections*

The connecting rod 30 is provided with a collar 33 and the upper end 34 of the rod telescopes through a block 35 pivotally mounted on the crank lever 36, the latter being pivoted as at 37 between the housings 14 and carrying a crank pin 38 to 25 which a link 39 is connected, the opposite end of this link being mounted on a pin 40 carried by a slide 41 mounted free to reciprocate on the pedestal 15.

An adjusting screw 42 is mounted on a cross- 30 bar 43 and its upper end comes in contact with a plug inserted in the underside of the lever 36, the screw 42 serving as a downward movement limit for the lever 36.

A pivot 44 is mounted in suitable bearings carried by the bed 13 adjacent the housings 14 and an angled lever 45 is mounted on this pivot, the horizontal portion of the lever being connected by a pair of links 46 to the horizontal portion of a lever 47, somewhat similar to the lever 45 and mounted at the upper portion of the housings 14 40 on a pin 48 having its bearing in the housings 14. A screw 49 is carried in cross bracket 50 which extends between the two housings 14 serving as a downward movement limit for the horizontal 45 portion of the lever 45. A block 51 is mounted as by trunnions between the two links 46 and above the upper surface of the lever 36 so that the upward movement of the lever 36 picks up the block 51 and raises the horizontal portions of the levers 45 and 47.

50 The vertical portion of the lever 45 carries a trunnioned block through which the adjusting screw 52 passes, this screw being provided with a nut at each side of the trunnioned block, the screw 52 being connected to a pivoted block 53 mounted on a pin 54, the latter being mounted in blocks 55 carried upon one end of a pair of rods 56 which are mounted to reciprocate in bosses 57 carried by the slide 41.

60 The vertical portion of the lever 47 carries a pin 58 upon which a cranked lever 59 is mounted, the horizontal portion of this lever being connected by links 60 to a shaft 61. The upper portion of the cranked lever 59 carries the pivotally mounted 65 horizontally arranged arm 62, one end of which is connected by a trunnioned block to the adjusting screw 63 which is pivoted to the horizontal portion of the lever 59 and is provided with hand wheels 64 and 65, by means of which the free end of the arm 62 may be raised or lowered.

70 The proportionate lengths of the portions of the levers 45 and 47 are such that when the lever 36 raises the links 46, the pivot pin 58 and the rods 75 56 move in the same direction to the same extent.

The pneumatic system

As shown more clearly in Figs. 2 and 3, the pneumatic system comprises an air supply pipe 66 which leads to a distribution chamber 67 within which is a slide valve controlled by valve rod 68 to admit air under pressure to pipe 69 and hose or flexible connection 70, pipe 69 extending upwardly and being connected to air cylinder 71 mounted upon the upper portions of the housings 14, the hose or flexible connection 70 being connected to air cylinder 72 which is indirectly carried by the knee 16 on the bed 13. As shown by dotted lines in Fig. 1, the air cylinder 71 is provided with a piston from which a piston rod 13 (see Fig. 4) extends upwardly and carries a block 74 on its upper end. The bifurcated lower end of member 75 is pivoted as by pin 76 to the block 74, the member 75 being fast upon the shaft 61, the upper end of this member comprising a cylindrical portion which serves as a counterweight. A block 77 is carried by the member 75 immediately above the block 74 and these two blocks form a movement limit for the swinging action of the member 75 in one direction as will be described later. When air under pressure is admitted through the pipe 69 to the cylinder 71, its piston is raised and through the linkage described the horizontal portion of the cranked lever 59 is raised and consequently the free end of the arm 62 is depressed to perform the functions to be later described.

Referring now more particularly to Fig. 9 the air cylinder 72 is provided with a piston 78 from which piston rod 79 extends to the interior of a 35 housing 80 carried by the knee 16. The piston rod 79 is connected by links 81 to lever 82 pivotally mounted in the housing 80, to operate a toggle mechanism to be later described.

To afford a quicker release, at the proper time, of the pressure within the cylinder 72, a housing 40 83 is mounted on the head of this cylinder and contains a release slide valve 84 operated by valve rod 85 from connections to be later described.

A compression spring 86 is provided to normally move the piston 78 toward the head of the 45 cylinder 72 and a similar spring, not shown, may be provided to move the piston in the air cylinder 71 downward upon the release of the pressure within that cylinder.

50 *Hub holding devices*

Referring more particularly to Figs. 1, 2, 3, 11 and 12, it will be noted that the rods 56 each carry a block 87 upon their ends opposite to that upon which the block 54 is mounted and by referring more particularly to Figs. 11 and 12, it will be seen that a pair of guides 88 are pivotally connected to the blocks 87 and 89 and are further connected to these blocks by adjusting screws 90 passing through arcuate slots formed in the 60 lower portion of the blocks 87. A rod 91 is mounted in each guide 88 and these rods are connected together at their lower ends by a bar 92 and at their upper ends by a plate 93 upon which is mounted the lower hub receiving die 94, Figs. 1, 65 2 and 3.

Referring again more particularly to Figs. 11 and 12, it is to be noted that a dot and dash center line 95 is shown parallel with the rods 91, and by loosening the screws 89 and 90, the guides 70 88 and the parts carried by them may be swung to bring the center line to the dotted line position 96 or to any other angular position required by the angular relation between the spokes of the wheel and the axis of its spindle.

Referring more particularly now to Figs. 1 and 2, it is seen that the arm 62 carries upon its free end an adjustable slide 97, adjusted in position by screws 98 and carrying upon its free end a cone 99 which is pivoted to the slide 97 and angularly adjustable thereon by set screws 100. The cone 99 moves down into and centers the upper end of a hub which is placed upon and engaged with the die 94, the latter being provided with a suitable recess or other device to engage the lower end of the hub.

The cone 99, after it has been adjusted to proper position both by means of the slide 97 and the set screws 100, has three movements, two of which are vertical, or substantially so, while the third is horizontal. The first and smaller of the two vertical movements is that produced by the admission of air under pressure to the cylinder 71 with the resulting raise of the horizontal portion of the cranked lever 59 and consequent depression of the cone 99. The second vertical movement is of greater magnitude than that just described. The shaft 61 which is located above the air cylinder 71 carries a crank 101 fast thereon, and this is connected, through rod 102, to bell crank 103, the latter being connected through rod 104 to hand lever 105 pivotally mounted on the bed 13, these parts being best shown in Fig.

1. When the upper portion of the lever 105 is moved to the left from its position shown in Fig. 1, the movements diagrammatically illustrated in Fig. 5 take place, the rod 102 moves upward to the dotted position 106 thereby moving the crank 101 to the dotted position 107 and swinging the member 75 to the dotted position 108, this member turning on the pivot 76, thereby moving the links 60 to the dotted position 109 and depressing the horizontal portion of the cranked lever 59 to the dotted position 110, turning this lever upon its pivot 58 and raising the cone 99 to a position considerably elevated above the upper end of the hub to permit the hub to be either placed upon the machine or removed therefrom.

The third or horizontal movement of the cone 99 is produced by the raising and lowering of the lever 41 through the links 46 and the consequent substantially horizontal movement of the pivot 58 during the operation of the secondary driving connections previously described.

50 After each spoke has been headed into the hub it is necessary to raise the hub and its spoke to disengage the spoke from the gripping dies which will be later described and this is accomplished as follows. Referring more particularly to Figs. 1, 3, 11 and 12, the bar 92 rests upon the bar 111 carried by a rocking lever 112 mounted in the upper end of a bracket 113 which is in turn mounted upon the side of the bed 13. The rocking lever 112 carries crank arm 114 which is connected through rod 115 with a pedal 116 mounted upon the bed 13 so that when the pedal is depressed the bar 111 is raised carrying with it the bar 92, rods 91, plate 93, hub die 94 and the hub with its spoke and consequently raising the cone 99 through a sufficient distance to permit the disengagement of the spoke from the gripping dies, attention being called to the fact that during this operation, the balance of the machine is at rest and the pressure is released from the air cylinder 71. The two bars 92 and 111 being arranged as they are crossing each other, perform this raising motion regardless of the angular adjustment of the guides for the rods 91.

Spoke heading tool

The spoke heading tool comprises an upwardly projecting stem 117 which carries, at its upper end, a button or projection 118, the stem 117 fitting into a holder carried by the slide 41. Referring more particularly to Fig. 10, the slide 41, at the end opposite that to which the link 39 is connected, is formed into a pair of plates spaced apart and perforated to receive the trunnions 119 carried by the holder 120 which has a socket 121 to receive the stem 117, set screws 122 being provided to hold the stem in any adjusted position. The holder 120 is arcuately formed at 123 to fit within the mating surface of the end of the slide 41 thereby relieving the trunnions 119 of the pressure during the heading operation. The lower end of the holder 120 is connected by rod 124 to a trunnioned block 125 mounted between the downwardly projecting portions of the slide under the pivot for the link 39, the rod 124 being threaded and provided with adjusting nuts adjacent the block 125 to the end that the holder 120 may be angularly adjusted and its center line moved from the dot and dash position 126 to a dotted position 127, this adjustment being for the same purpose as the adjustment previously described in connection with Fig. 11.

Spoke gripping dies

The upper portion of the housing 80 which is carried by the knee 16 is provided with a pair of spoke gripping dies 128 and 129, the former being carried by the cover plate 130 while the latter is carried by the slide 131, which has its bearings in the upper portion of the housing 80. The housing 80 is vertically adjusted on the knee 16 by means of any suitable lead screw 132 and is held in adjusted position by clamp screws 133, Figs. 1, 2 and 3. Vertical adjustment of the spoke gripping dies through the mechanism just described permits these dies to be set in proper relation to the hub carrying die 94 to accommodate the difference in distance from the end of the hub to the center of the spoke on different types of hubs, and this vertical adjustment of the dies 128 and 129 is accompanied by a corresponding adjustment of the stem 117 of the heading tool in its holder 120 to the end that the button 118 will be in alignment with the spoke receiving grooves of the gripping dies.

The knee 16 is longitudinally adjustable on the bed 13 by means of a lead screw operated by the hand wheel 134 and is held in adjusted position by clamp bolts 135 as well as nuts 136 on the tie rods 137 which pass through bosses 138 on the upper portion of the knee 16 and extend to the housings 14 as shown in Figs. 1, 2 and 3.

The slide 131 is provided with a vertically arranged pocket within which a pair of blocks 139 are fitted the latter being shaped to fit the rounded upper end of the lever 140 which is pivoted as at 141 in the housing 80. The lower end of the lever 140 is attached to the link 142 and this link is in turn attached to a link 143, the latter pair of links forming a toggle, the link 143 being pivoted as at 144 to the upper forked end of the lever 82. The link 143 is provided with a heel 145 which rests against a corresponding portion on the lever 82, the latter also carrying a lug 146 through which a rod 147 passes, the upper end of the rod being pivoted to the link 143, the lower end of the rod being provided with compression spring 148 bearing against the underside of the lug 146. When the air is released from the cylinder 72, the spring 148 moves the

piston to the right in Fig. 9, carrying with it the link 81, the lever 82 and through the contact between this lever and the heel 145 of the link 143 breaks the toggle between the links 142 and 143 and moves the upper end of the lever 140 to the left to move the gripper 129 also to the left, this being the release position of the gripper dies. When air is admitted to the cylinder 72 the piston 78 moves to the position shown in Fig. 9 but if the spoke inserted between the gripper dies 128 and 129 should happen to be too large, the toggle levers 142 and 143 will not come to a straight line position, the spring 148 being compressed thus permitting the piston 78 to move its full stroke 15 without danger of breaking any of the linkage.

Control device

Referring now more particularly to Figs. 2, 3, 4 and 6. The main control pedal 149 is mounted 20 on cross shaft 150 which carries crank arm 151 projecting upwardly on the opposite side of the bed from that on which the pedal 149 is mounted, and the upper end of crank arm 151 is connected through rod 152 with the clutch operating rod 25 153. This rod carries a block 154, the latter being provided with lateral arms 155 and 156. The arm 155 embraces a rod 157 which is provided with a spring 158 and which operates clutch yoke 159 which is pivotally mounted on the bracket 160, 30 the latter serving also as a guide for the clutch operating rod 153. The clutch yoke 159 engages the member 28 of the dental clutch and when the clutch operating rod 153 is drawn to the right in Fig. 3, the spring 158 being compressed by the 35 movement of the arm 155 shifts the clutch 28 into engagement with its mating member 27 on the gear 25. Referring now more particularly to Fig. 6, it is to be noted that the rod 153, when the clutch is disengaged, lies within the groove engaged by the yoke 159 and as shown by the dotted 40 line 161, there is a raised portion adjacent this groove and a second raised portion adjacent the first, making, in effect, three different longitudinal positions for the rod 153, either at the bottom of the groove as shown in Fig. 6, or upon the step 161, or upon the outer diameter of the member 28. When the rod 153 is pulled to the left in Fig. 6, and the clutch moves into engaged position, the right hand end of the rod 153, in Fig. 6, 45 rests upon the large diameter of the clutch which coincides with the diameter of the disc 31, the end of the rod resting upon an inserted cam 162, and as the clutch rotates, turns clockwise when viewed from the position of Fig. 6, the rod 153 moves in to 50 the diameter 161, still not relieving the tension on the spring 158 and as the clutch completes one revolution, the end of the rod 153 acts upon the cam 162 definitely disengages the clutch whereupon the rod 153 moves into the shifter groove 55 and again assumes the position shown in Fig. 6.

Still referring to Fig. 6, the arm 156 of the block 154 carries a pin which engages a rocking lever 163, which is pivoted on the bracket 160 and carries a trigger 164, the latter normally elevated at 60 its free end by the tension spring 165. The trigger 164 passes through a slotted lever 166 carried on a rock shaft 167 mounted in suitable bearings upon the frame 17, as shown in Figs. 2, 3 and 4. A pin 168 passes through the slot in the lever 166 and is engaged by a detent 169 carried by the trigger 65 164.

When the clutch shifter rod 153 is moved as previously described, to engage the clutch, the center line of the lever 163 moves to the dotted 70 position 170, and the detent 169 coming in contact

with the pin 168 of the lever 166 moves this lever to the dotted position 171, the trigger meanwhile moves to the dotted position 172. As the clutch 28 is rotated by its engagement with the clutch 27 of the gear 25, the pin 32 carried by the disc 31 moves toward the right and then down and first depresses the trigger 164 to disengage its detent 169 from the pin 168 and then comes in contact with the lever in the position 171 and moves it to the full line position of Fig. 6. From the above it will be seen that when the clutch is engaged, the rock shaft 167 is moved clockwise and that when the clutch has completed approximately one half of its revolution, the rock shaft 167 is moved counter-clockwise, and that upon the completion of the revolution of the clutch the parts are all restored to their full line positions of Fig. 6, the detent 169 again being ready to engage the pin 168 upon the next operation of the clutch.

The rock shaft 167 carries two crank arms one 20 projecting above and the other below it. The crank arm 173 is connected by rod 174 to the valve rod 68 while the crank arm 175 projecting below the rock shaft 167 is connected by rod 176 with a crank 177 on a second rock shaft 178, the latter 25 carrying a crank 179 which, at its upper end carries a pivoted connecting piece 180 through which the valve rod 68 passes.

From the above it will be seen that when the clutch 28 is engaged, the mechanism just described 30 will open the valve in the housing 67 and supply both the cylinders 71 and 72 with air under pressure from the pipe 66, and that when the clutch has made one-half a revolution, the valve in the housing 67 will be closed to release the air from both cylinders 71 and 72, and in addition, the exhaust valve 84 in the housing 83 will be opened to permit a more rapid escape of the air from the cylinder 72 and a consequent quicker opening and release of the gripping dies 128 and 129.

To assist in maintaining the lever 166 in either its full line or its dotted line position, the tension spring 181 is provided and this spring crosses the center of the rock shaft 167 as the lever 166 is moved from one position to the other so that the spring acts to hold the lever in either its vertical or angular position, the free end of the spring being attached to a standard 182, dotted lines Fig. 2, carried by the base 17, eyebolt 183 serving as an adjustable connection at this point.

Operation of the machine

The preliminary setting of the machine consists in placing the proper hub die 94 on its plate 93, supplying the proper headforming tool 117 and 55 adjusting the angular relation of these parts to the hub within which the spokes are to be placed. In addition, the cone 99 is brought to proper position with relation to the upper end of the hub and gripping dies 129 of the proper size and 60 mounted to receive and properly hold the spokes. The elevation of the gripping dies and the head-forming tool 117 is properly set, through the means previously described, to hold the spoke at proper distance from the end of the hub. The proper point for the beginning of the heading stroke is set by means of the hand wheel which 65 operates the screw 49 and also the jack screw 42, these two adjustments determining the point of beginning of the heading stroke (the termination of the heading stroke is constant, the length of the stroke being determined by the adjustment of its beginning).

With the lever 105 moved to the left in Fig. 1, 70 to elevate the cone 99, the operator places a hub 75

upon the machine and moves the lever to the right bringing the cone into contact with the upper end of the hub whereupon he rotates the hub to bring one of the spoke openings into proper position with relation to the groove in the stationary spoke gripping die. He next places a heated spoke in the groove of the stationary gripping die and advances it to contact with the button 148 (Fig. 7). He next depresses the pedal 10 149 and this causes the following operations to be performed in the following sequence.

First.—Air is admitted to the two cylinders 71 and 72 and this firmly grips both the hub and the spoke.

15 Second.—When the clearance between the connecting rod 30 and its block 35 has been taken up by the rotation of the crank disc 29, the heading tool 117 as well as the hub carrying die are advanced to head the spoke inside and outside of the hub as shown in Fig. 8.

Third.—At the completion of the heading stroke the pin 32 by coming in contact with the trigger 164 and lever 166, previously described, releases the air from cylinders 71 and 72, thus releasing the spoke and relieving the hub of its clamping pressure from the cone 99.

Fourth.—The second half revolution of the clutch brings the heading tool 117 and the hub holding dies back to the position they occupied at the beginning of the stroke and the crank disc 29 comes to rest, being assisted in this operation by a brake 184 Figs. 1 and 4, which bears against the outer surface of the disc, the latter being cam-shaped to relieve the brake pressure during part of its rotation.

By depressing the pedal 116, through the mechanism previously described, the hub and its spoke are raised so that the spoke clears the upper portion of the gripping dies, the spoke now being used as a handle to rotate the hub to the next spoke hole whereupon the pedal 116 is released, the next spoke inserted, the pedal 149 depressed, and the operation previously described repeated. When all the spokes at one end of the hub have been headed thereinto, the lever 105 is again operated to raise the cone 99 to permit the position of the hub with its spokes to be reversed so that the spokes adjacent the opposite end of the hub may be headed into it by a repetition of the operations just described.

When the adjustment of the machine makes it necessary to move the knee 16 or the housing 80, or both, obviously the valve rod 85 will require readjustment and to this end this rod is provided with a collar near the housing 83 and the pivoted connecting piece 180 is provided with a screw, and by loosening this screw and setting the collar to a definite distance from the end of the stuffing box of the housing 83, and then tightening the screw of the piece 180, the valve rod 85 may be reset for the new position to give the proper opening and closing motions when the machine operates.

The amount by which the heading tool 117 and its button moves further than the hub die 94 determines the amount of material gathered for the head on the spoke on the inside of the hub while the amount of movement of the hub carrying die 94 determines the amount of material contained in the collar on the spoke outside the hub, hence by adjusting the beginning of the stroke for these two operations, a proper distribution of the spoke material may be had to form the head and the collar at the hub.

Having thus fully described my invention, I claim:

1. In a machine of the class described, the combination of a spoke heading tool support member, a laterally movable support therefor, means for adjusting the tool support member angularly relative to its support, a hub-receiving member supported upon the tool support member and movable relative thereto the same being angularly adjustable with respect to the tool support, power connected means for moving said tool support and hub receiving members, means for adjusting the hub receiving member in accordance with adjusted position of the tool support member and relative to the power connected means, a spoke gripping mechanism, a hub holding member cooperative with the receiving member and adjustable in accordance with adjusted position thereof and means for moving the holding member vertically relative to the receiving member or laterally in unison therewith, the first named movement being accomplished by means of a mechanism comprising a power driven crank member 29, a lever member, 36, operatively connected therewith, the latter having operable connection with said tool support and hub receiving members in such a manner as to impart movement to each of said members at dissimilar speed and of dissimilar extent movement of the hub holding member being accomplished through a mechanism including, a second lever, 47, having operable connection with an arm of the first named lever, a third lever, 59, pivotally supported on the opposite arm of the second lever, an arm adjustably supported upon one arm of the third lever, the same carrying said hub holding member, the opposite arm thereof having connection with a toggled linkage, one element of which is connected with the plunger of an air cylinder, another element being connected with a hand lever, the latter adapted to move the linkage into position whereby movement of said plunger imparts movement to said third lever and arm or to move the linkage in such a manner as to directly impart movement to said arm independently of the plunger, whereby with a hub placed upon the receiving member movement of the hand lever brings about movement of said holding member into contact with the hub and placement of said linkage in position described to be operated upon by said plunger, whereupon pneumatic operation of the plunger results in additional forced movement of the holding member to securely hold the hub upon the receiving member.

2. In a machine of the class described, the combination of a spoke heading tool support member, a laterally movable support therefor, means for adjusting the tool support member angularly relative to its support, a hub receiving member supported upon the tool support member and movable relative thereto the same being angularly adjustable with respect to the tool support, power connected means for moving said tool support and hub receiving members, means for adjusting the hub receiving member in accordance with adjusted position of the tool support member and relative to the power connected means, a spoke gripping mechanism, a hub holding member cooperative with the receiving member and adjustable in accordance with adjusted position thereof, means for moving the holding member vertically relative to the receiving member or laterally in unison therewith, the latter movement being accomplished by means of a mechanism comprising

a power driven crank member, a lever member operatively connected therewith, the same having operable connection with said tool support and hub receiving member in such a manner as to
5 impart movement to each of said members at dissimilar speed and of dissimilar extent, a second lever having operable connection with an arm of the first named lever, a third lever pivotally supported on the opposite arm of the second lever,
10 an arm adjustably supported upon an arm of the third lever, the same carrying said hub holding member, said arm and third lever assembly being laterally movable by means of pivotal movement of said second lever as brought about by movement
15 of the first named lever, the above described mechanism operable to bring about lateral movement of said hub receiving member and unitary lateral movement of said holding member.
3. In a machine of the class described, the combination of a spoke heading tool support member,
20 a laterally movable support therefor, means for adjusting the tool support member angularly relative to its support, a hub receiving member supported upon the tool support member and movable relative thereto the same being angularly adjustable relative to the tool support, a hub holding member cooperative with the hub receiving member and movable in unison therewith, means for
25 adjusting the hub receiving member in accordance with adjusted position of the tool support member, power connected means for bringing about movement of the tool support and hub receiving members in an accompanying manner but at dissimilar speed and of dissimilar extent comprising a power driven crank member, a lever member operatively connected therewith, the latter having operative connection with mechanism for moving
30 said hub holding member and with a second lever,
35 the first named lever also having operative connection with said heading tool support member, whereby rotation of the crank brings about lateral movement of the heading tool support member, the second named lever having adjustable operative connection with said hub receiving member to move the same upon the tool support member.

second lever, 45, the first named lever also having operative connection with said heading tool support member whereby rotation of the crank brings about lateral movement of the heading tool support member, the second named lever having adjustable operative connection with said hub receiving member to move the same upon the tool support member. 5

4. In a machine of the class described, the combination of a spoke heading tool support member, 10 a laterally movable support therefor, means for adjusting the tool support member angularly relative to its support, a hub receiving member supported upon the tool support member and movable relative thereto, a hub holding member cooperative with the hub receiving member and movable in unison therewith, means for adjusting the hub receiving member in accordance with adjusted position of the tool support member, 15 manual means for moving the hub receiving member vertically relative to the tool support member, power connected means for bringing about movement of the tool support and hub receiving members in an accompanying manner but at dissimilar speeds and of dissimilar extent comprising a power driven crank member, a lever member operatively connected therewith, the latter having operative connection with mechanism for moving said hub holding member and with a second lever, 20 the first named lever also having operative connection with said heading tool support member, whereby rotation of the crank brings about lateral movement of the heading tool support member, the second named lever having adjustable operative connection with said hub receiving member to move the same upon the tool support member. 25
